FIG. 5

INVENTOR:

CHARLES F. PAULUS

BY
Fred L. Fraenke

ATTORNEY

UNITED STATES PATENT OFFICE.

CHARLES F. PAULUS, OF NEWARK, NEW JERSEY.

TOY PISTOL.

SPECIFICATION forming part of Letters Patent No. 707,252, dated August 19, 1902.

Application filed December 19, 1901. Serial No. 86,499. (No model.)

To all whom it may concern:

Be it known that I, CHARLES F. PAULUS, a citizen of the United States, residing at Newark, in the county of Essex and State of New Jersey, have invented certain new and useful Improvements in Toy Pistols; and I do hereby declare the following to be a full, clear, and exact description of the invention, such as will enable others skilled in the art to which it applies to make and use the same, reference being had to the accompanying drawings, and to figures of reference marked thereon, which form a part of this specification.

The present invention relates to improvements in toy pistols for the firing of paper or fulminating caps; and the invention has for its principal object to provide a toy pistol in which the paper cap is inserted through a slot or opening in the top of the pistol-frame and arranged directly in a slotted receiving portion of a combined trigger and hammer, producing what may be termed a "center-firing" pistol, in which there is no possibility of the flash from the exploding cap being forced from the sides of the pistol, as is ordinarily the case in the constructions of toy pistols as now made.

Other objects of this invention are to provide a simple, durable, and cheaply-constructed toy pistol of the character hereinafter fully set forth which is of such a construction that all danger of burning the person handling the pistol is entirely overcome.

With these several objects in view my invention consists of the novel construction of toy pistol hereinafter set forth, provided with a cap-receiving hammer; and, furthermore, this invention consists in the several novel arrangements and combinations of the various parts, as well as in the details of the construction thereof, all of which will be fully described in the following specification and then finally embodied in the clauses of the claim.

The invention is clearly illustrated in the accompanying drawings, in which—

Figure 1 is a side elevation, and Fig. 2 a top edge view, of a pistol embodying the several novel features of the present invention. Fig. 3 is a longitudinal vertical section of the pistol, illustrating the arrangement of the cap-receiving hammer of the pistol in its position against an exploding or firing anvil, but the paper cap having been omitted; and

Fig. 4 is a similar view of the said parts represented in said Fig. 3, but illustrating the cap-receiving hammer in its actuated position directly beneath the opening or slot in the upper edge of the pistol-frame for receiving a paper cap. Fig. 5 is a perspective view of the paper-cap-receiving portion of the hammer.

Similar characters of reference are employed in all of the said above-described views to indicate corresponding parts.

Referring to the said drawings, the reference-numeral 1 indicates the complete toy pistol for firing paper caps, the said pistol comprising a pair of pistol-sections 2 and 3, which are adapted to be placed upon each other in the manner illustrated in Fig. 2 and are secured together to form a hollow or chambered pistol-frame by means of suitably-disposed pins or rivets 4 and 5. The pistol-frame thus formed is made with the usual stock 6 and with the barrel 7.

As will be seen from the several figures of the drawings, each pistol-section is made with a marginal projection or shoulder, as 8, the marginal shoulder of each section being provided in its upper portion with a laterally-extending slot 9 in the pistol-section 2 and with a laterally-extending slot 10 in the pistol-section 3. When the two pistol-sections are secured together to form the complete pistol-frame, then these said slots 9 and 10 are arranged directly opposite one another, as indicated in Fig. 2 of the drawings, and thereby providing a cross slot or opening in the upper edge of the pistol, through which a paper cap can be inserted, so as to be arranged in the slotted end of a hammer, substantially as and for the purposes to be presently described. In the lower portion of the said marginal shoulders 8 of each pistol-section is an opening 11, in which is pivotally arranged upon a pivot or pin 12 a firing-hammer 13. This hammer 13 is provided in its upper end portion with a slotted or other suitably-constructed cap-receiving portion 14, which can be brought directly beneath the opening formed by the slots 9 and 10 in the two pistol-sections 2 and 3 when in the position indicated in Fig. 4 of the drawings, so that said cap-receiving portion in the hammer 13 will register with the said opening in the pistol-frame and is thereby adapted to receive a paper cap, which is inserted into and through

the said opening formed by the slots 9 and 10, as will be clearly understood. The said hammer 13 is also provided, directly back of its cap-receiving portion 14, with a suitably-arranged hole or perforation 15, and at its lower end it is formed with a trigger or finger-piece 16, which projects from the bottom of the pistol-frame through the opening 11 in the said pistol-sections 2 and 3, which produce said frame. The said hammer 13 is also provided with a suitably-disposed eye 17, to which is attached one end of a spiral spring 19, the said spring having its opposite end secured to a pin 18, substantially as illustrated. Each pistol-section is also provided upon its inner surface with an enlargement or projection 20; forming a firing or exploding anvil, and with a firing pin or projection 21, as illustrated in Figs. 3 and 4 of the drawings.

The manner of loading and firing the pistol is as follows: The operator places his finger upon the rounded surface of the trigger or finger-piece 16, thereby forcing the main body of the hammer 13, against the opposing tension of the coiled spring 19, directly against a pin or stop 22, formed on the inner surface of one or both of said pistol-sections 2 and 3. The hammer 13 is thus brought from the position indicated in Fig. 3 of the drawings to that represented in said Fig. 4, causing its cap-receiving end 14 to register with the slot or opening formed by the two slits 9 and 10, as shown, and a paper cap or fulminate can be passed directly through the said opening in the upper portion of the pistol-frame and deposited directly in the cap-receiving end 14 of the hammer. As soon as the finger is forced over the rounded portion of the said trigger or finger-piece 16 the spring 19 brings the upper cap-retaining portion of the hammer and the paper cap therein forcibly against the firing pin or projection 21 of the anvil 20, whereby the cap is exploded with a loud report. At the same time the fire from the exploding paper cap will pass directly through the hole or perforation 15 in the hammer and pass into the tubular portion of the barrel 7 of the pistol. In this manner I have produced a center-firing pistol for exploding paper or percussion caps, and the pistol construction is such that all fire from the exploding caps is retained directly within the chambered part of the pistol-frame and passes out of the barrel without the least danger of a person being burned or harmed by the flashes of the burning powder, as in the constructions of paper-cap pistols in which the cap is exploded directly upon the outer side of the pistol-frame and in front of a descending hammer. Furthermore, there is no exposing slot or opening either in the top or in the sides of the pistol at the point where the cap is exploded, and a novel and efficient construction is thus produced in which all fire from the exploding caps is retained directly within the pistol-frame without the least dan-

ger of being burned, as heretofore, when the pistol is carelessly handled.

Of course I am aware that changes may be made in the various arrangements and combinations of the parts, as well as in the details of the construction of the hammer and trigger mechanism, without departing from the scope of my present invention. Hence I do not limit my invention to the exact arrangements and combinations of the parts as described in the specification and as illustrated in the drawings, nor do I confine myself to the exact details of the construction of the various parts.

Having thus described my invention, what I claim is—

1. In a toy pistol, the combination, with a chambered pistol-frame having an opening in its upper surface through which a cap can be inserted, of a pivoted hammer within said pistol-frame, provided in its upper portion with a cap-receiving part, adapted to register with the said cap-inserting opening in the pistol-frame, and means within said pistol-frame against which said cap-receiving part is brought for exploding the cap, substantially as and for the purposes set forth.

2. In a toy pistol, the combination, with a chambered pistol-frame having an opening in its upper surface through which a cap can be inserted, of a firing-anvil and a firing-pin on said anvil, both said anvil and firing-pin being arranged within said pistol-frame, a pivoted hammer within said frame, a cap-receiving part upon the upper portion of said hammer, said cap-receiving part having a hole or perforation, and the said cap-receiving part being adapted to register, first, with the said cap-inserting opening in the upper surface of the pistol-frame, and, secondly, with the firing-pin on said anvil for the explosion of the cap, substantially as and for the purposes set forth.

3. The herein-described toy pistol, comprising, a pair of pistol-sections, means for securing them together to form a chambered pistol-frame, having a cap-inserting opening in the top of the frame, a firing-anvil and firing-pin in said frame, a spring-actuated hammer pivotally arranged within said frame, a cap-receiving part in the upper end of said hammer adapted to receive a paper cap, a trigger or finger-piece extending from the under part of the pistol-frame, said trigger forming a part of said hammer, and a stop in said frame against which the hammer is brought to limit the forward movement of said hammer and cause said cap-receiving part in the hammer to register with the cap-inserting opening in the pistol-frame, and to receive the cap, substantially as and for the purposes set forth.

In testimony that I claim the invention set forth above I have hereunto set my hand this 18th day of December, 1901.

CHARLES F. PAULUS.
